UNITED STATES PATENT OFFICE.

WILLIAM J. BEACH, OF TORONTO, ONTARIO, CANADA.

LOUD-SPEAKING RECEIVER.

Application filed March 30, 1925. Serial No. 19,299.

To all whom it may concern:

Be it known that I, WILLIAM J. BEACH, a citizen of the Commonwealth of Australia, and a resident of Toronto, county of York, and Province of Ontario, Canada, have invented a new and useful Improvement in Loud-Speaking Receivers, of which the following is a specification.

My invention relates to loud speaking receivers and pertains to the electro-magnetic type of such receivers which perhaps find their chief use in connection with radio reception.

The principal objects contemplated by my invention comprise producing a loud speaker which is extremely efficient in sound reproduction, both from the standpoint of volume and clarity of reproduction; to provide a micrometer adjustment between the electro-magnetic elements to ensure high quality of reproduction; to provide a device in which the various parts are freely accessible; to provide a sound chamber which may be acoustically tuned and in which the means for reproducing the sound are contained in the chamber; and further to provide a device, the diaphragm of which is such that equal tonal value is given to the reproduction of sound therefrom by each of the diaphragm surfaces.

I accomplish all these very desirable features and others, which will hereinafter be discussed, by means of the novel device described in the specification and illustrated in the drawings which accompany and form a part of this specification.

In the drawings, in which like numerals designate corresponding parts throughout:

40 Fig. 1 is a side elevation of my complete device.

Fig. 2 is a broken elevation of the same with the outer cover and flare removed.

Fig. 3 is a front view taken on the line 45 3—3 of Fig. 2.

Fig. 4 is a broken sectional view of a portion of the device taken on the line 4—4 of Fig. 3.

Fig. 5 is a front view of a portion of the 50 device taken on the line 5—5 of Fig. 2.

Fig. 6 is a sectional view of the sound deflecting member taken on the line 6—6 of Fig. 5.

Fig. 7 is a front view taken on the line 55 7—7 of Fig. 2.

Fig. 8 is a broken sectional view of the diaphragm of the device taken on the line 8—8 of Fig. 7.

Fig. 9 is a detail view of the permanent magnet.

Fig. 10 is a fragmentary view of the permanent magnet with the extension pole and pole pieces in position.

Fig. 11 is a modification of the electro-magnetic system of Figs. 9 and 10.

Fig. 12 is a side view of one of the pole pieces.

Referring now to Figs. 1 and 2 particularly, my device comprises a containing and supporting casing or housing 1, which is 70 preferably cast of aluminum in the form of three co-axial right cylinders of variant diameter. The largest of these cylinders supports a bell or flare 2 which is the acoustic outlet of the speaker. The device 75 as a whole is adapted to be supported by a base 4 which supports a rotatable stud 54 provided with a knurled adjustment wheel 5 by which the device may be rotated in a horizontal plane. The stud 54 further 80 supports a bracket 3 in which the device is journaled as shown to permit the device to be rotated in a vertical plane. The knurled knobs as 6 are provided to clamp the device at any desired vertical angle. A 85 removable plate 12 is provided whereby the interior mechanism of the device may be viewed for adjustment purposes, as will hereinafter be explained.

Referring now particularly to Fig. 2 in 90 which the casing 1 is represented in dotted outline and the flare or bell 2 is omitted, my device comprises a mechanism supporting member 14 adapted to slide within the middle portion of the outer casing 1 as 95 shown. The member 14 is cast of aluminum in the form of a hollow cylinder provided with a flange 94 and a collar 18 of larger diameter than the body of the member. The rear portion of the member is closed by 100 a plate 55 secured to the member by screws as shown. The plate 55 carries a central boss 56. A push rod 15 which is threaded into the outer casing 1 and provided with a knurled knob 9 is further provided with 105 a plate 57 adapted to make contact with the boss 56 carried by plate 55. A calibrated dial 11 is provided on the casing 1 and a pointer 10 is attached to the push rod 15, thus providing a means for accurately 110

adjusting the position of the member 14 within the casing 1, for a purpose which will be hereinafter described. The flange on the member 14 is provided with apertures 5 therein to freely slide over studs 17, 47, 77 and 87, which are screwed into the casing 1 as indicated. Springs 16 and 46 are provided between the cap of each of the studs 17, 47, 77 and 87 and the flange of the member 14 and exert pressure to keep the member always in contact with the enlarged end of the push or adjusting rod 15.

As shown in Fig. 3, a permanent magnet 19 of substantially circular form is carried 15 within the collar 18 of the member 14 and is held in place thereby by means of lugs 20 and 60 which are secured to the collar of the member 14 and in which are secured set screws 22 and 62 to retain the permanent 20 magnet 19, as shown in Figs. 3 and 4. A guide web 21 is provided and secured to the member 14, as indicated in Fig. 3. Extension pole pieces 24 and 64 are secured to the permanent magnet 19 and extend toward 25 the centre thereof and serve to support pole pieces 42 and 62 and operating magnet coils 23 and 63, connections 27 for which pass through a slot 26 in the member 14 and are connected to binding posts as 7 and 8, 30 Fig. 1.

As shown in Figs. 3 and 4, the operating magnets are held securely in position by means of screws as 25 and 95, which are threaded into bosses on the member 14. An 35 armature 80 is maintained adjacent to the pole pieces of the operating magnets 23 and 63 and is provided with a rod 34 attached thereto, which passes through a central guide aperture 35 in the guide web 21 and 40 further through an aperture in a sound deflecting member 28, which is shown in Figs. 5 and 6.

This sound deflecting member 28 is formed in the shape indicated and is movable longitudinally within the member 1. 45 It is held in place by means of studs as 49 carried in slots 29 and 59 and provided with spring clips as 13. The central aperture in the sound deflecting member 28 is of such 50 diameter as to give full clearance for the rod 34. The extremity of the rod 34 as shown in Figs. 7 and 8 is securely clamped as indicated in Fig. 8 to the mid portion of two cone shaped diaphragms 32 and 33 55 which are clamped between retaining rings as 36 and 37 and a spacer 30, all of which are provided with a series of annular sound outlets or ports as 38 located near the outer periphery of the diaphragms. The diaphragm organization is held in the casing 1 by means of screws as 31. The clamping 60 means which secures the rod 34 to the diaphragms further functions as a means for tensioning or stretching the diaphragms.

65 It will be noted from the foregoing that

the knurled knob 9 may be operated to push the member 14 carrying the electro-magnetic organization against the pressure exerted by the springs 16 and 46 to vary the distance between the pole pieces and the armature 70 80 carried by the rod 34, which passes through the guide web 21, the sound deflecting member 28 and is attached to the cone shaped diaphragms 32 and 33. The distance between the armature and pole pieces 75 may be observed through the port in the casing 1 closed by the plate 12. The guide web 21 acts, as its name implies, to constrain the vibrations of the rod 34 axially and to prevent any lateral motion thereof. 80 It will be noted that the sound deflecting member 28 is held by means of the three spring clips as 13 and may be moved toward or away from the diaphragms to vary the acoustic period of the sound chamber 85 formed between the sound deflecting member and the diaphragms. It will be further noticed that the apexes of the two diaphragms meet and that the diaphragm as a whole comprises an annular ring of air, the cross 90 section of which is triangular with the apex at the centre thereof. It should be further noticed, by reference to Fig. 4, that the extension pole pieces as 24 and 64 comprise laminations which are secured to the per- 95

manent magnet either by the method indicated in Figs. 9 and 10 or the method indicated in Fig. 11. In the method indicated in Figs. 9 and 10 a series of slots as 40 are provided in the permanent magnet in which 100 the laminations as 41 are introduced. The laminations are carried through the operating coils and serve as the operating pole pieces shown as 42. The laminations are held in the permanent magnet by means of 105 a clamping screw as 22, while the laminations 42 carrying the coil 23 are held in the extension pole laminations 41 by means of screws 25 and 95 which clamp the organization to the member 14, as shown in Figs. 110 3 and 4. An alternative method of connecting the extension pole piece laminations is shown in Fig. 11, in which they are shown as composed of two groups 43 and 44 carried on either side of the permanent magnet 115 39 and in turn carrying the pole piece laminations 42. The operating extremity or pole face of the pole piece laminations 42 are serrated as shown in Fig. 12.

The operation of the polarized electro-magnetic organization is so well known in the art as to need no explanation here, and it is deemed sufficient to explain and discuss the characteristics of the novel features of my device. The provision of 120 laminated extension pole pieces which are secured to slots provided therefor in the permanent magnet ensure the efficiency of the transfer of magnetic energy due to a 125 more even and more intimate connection 130

between the extension pole piece and the permanent magnet. Further, the provision of a visible micrometer adjustment between the operating pole faces and the armature 5 provides an extremely close adjustment which ensures high quality of reproduction. The provision of a guide as 21 to prevent lateral motion of the rod connecting the armature 80 with the diaphragms ensures 10 that all motion imparted by the armature to the diaphragms will be along the axis of the rod and thus prevents lost motion and ensures ample volume. The provision of the double cone shaped diaphragms ensures 15 that each surface of the diaphragm will be similarly utilized in the production of the sound wave and the air chamber between the diaphragms acts as an acoustic loading for the device to prevent distortion. 20 Further, the provision of the sound deflector serves to prevent reflection of sound into the operating mechanism of the device and to reflect sound from the surface of the inner diaphragm through the annular ports 25 as 28 which surround the diaphragm mechanism as a whole. The sound deflector 28 may be moved to tune the resonant chamber as desired to improve the quality of reproduction. It will be noticed in my device 30 that the acoustic outlet 2 or bell is at no place throughout its length of smaller diameter than the diameter of the diaphragms, thus there can result no acoustic choking, which is found to be detrimental in other 35 devices of this class.

From the above it will be noted that I have produced a device which will be effective in the translation of electrical energy into sound waves with the highest efficiency. That I have further produced a device embodying features tending to increase the tonal quality of such reproduction, by refinements of adjustment and by refinements of tuning the acoustic chamber 45 and efficiently directing the sound therefrom.

While I have disclosed and described but one embodiment of my device, I wish it to be clearly understood that I may vary the 50 details thereof without departing from the spirit or narrowing the scope of my invention.

Having thus fully described my invention what I claim as new and desire to secure by 55 United States Letters Patent is as follows:—

1. In a loud speaking receiver, an electro-magnetic system, an armature operated thereby, a diaphragm operated by said armature, a sound deflector disposed between said electro-magnetic system and said diaphragm, and sound ports near the outer periphery of said diaphragm to permit egress of sound reflected from said sound 60 deflector.

2. In a loud speaking receiver, an electro-magnetic system, an armature operated thereby, a diaphragm operated by said armature, a sound deflector disposed between said electro-magnetic system and said diaphragm, and sound ports at the outer periphery of said diaphragm to permit egress of sound reflected from said sound deflector. 70

3. In a loud speaking receiver, an electro-magnetic system, an armature operated thereby, a diaphragm operated by said armature, a sound deflector disposed between said electro-magnetic system and said diaphragm and adjustable with respect to its distance from said diaphragm, and sound 75 ports near the outer periphery of said diaphragm to permit egress of sound reflected from said sound deflector.

4. In a loud speaking receiver, an electro-magnetic system, an armature operated thereby, a diaphragm, a connection between said armature and said diaphragm, a guide for said connection, a sound deflector disposed between said electro-magnetic system and said diaphragm, and an acoustic outlet the 80 minimum diameter of which is substantially the same as that of said diaphragm. 85

5. In a loud speaking receiver, a housing, supporting means for said housing, an acoustic outlet mounted on one extremity 95 of said housing, a support adapted to permit said housing to be rotated in two planes, an electro-magnetic system within said housing, a diaphragm, a sound deflector disposed between said electro-magnetic system and said diaphragm and means whereby 100 said deflector may be moved relatively to said diaphragm.

6. In a loud speaking receiver, a housing, a flare mounted on said housing, means for supporting said housing whereby said housing may be moved in two planes, a polarized electro-magnetic system, an armature therefor, a diaphragm comprising two cone shaped members with their apexes in contact, a rod connecting the apexes of said diaphragms to said armature and a guide for said rod. 105

7. In a loud speaking receiver, a housing, a flare mounted on said housing, means for supporting said housing to permit movement thereof in two planes, a polarized electro-magnetic system, an armature therefor, a rod, a diaphragm connected to said armature through said rod, a guide for said rod 110 and a visible micrometer means for adjusting the distance between said electro-magnetic system and said armature. 115

8. In a loud speaking receiver, a permanent magnet, extension pole pieces therefor comprising laminations adapted to make contact with said permanent magnet at a plurality of positions with respect to the cross section thereof, laminated pole pieces carried by said extension pole pieces, operat- 120 125 130

ing electro-magnets disposed on said pole cross section thereof, laminated pole pieces pieces; an armature, micrometer means for adjusting the distance between said pole pieces and said armature and a diaphragm 5 adapted to be operated by said armature.

9. In a loud speaking receiver, a permanent magnet, extension pole pieces therefor comprising laminations adapted to make contact with said permanent magnet at a 10 plurality of positions with respect to the

carried by said extension pole pieces the laminations being of variant lengths to present serrated pole faces, operating electro-magnets disposed on said pole pieces, an 15 armature, micrometer means for adjusting the distance between said pole pieces and said armature and a diaphragm adapted to be operated by said armature.

WILLIAM J. BEACH.
